REMOVABLE CONCRETE INSERT PLUG

Ira G. Haskell, San Francisco, Calif.

Application May 25, 1943, Serial No. 488,380

8 Claims. (Cl. 25—118)

The present invention relates to removable concrete insert plugs, and in particular to such devices as are adapted to position a threaded nut or similar operation into a body material wherein it is desired to have an imbedded nut. The invention finds special advantage in positioning nuts in concrete, mortar and the like which are poured or applied in semi-fluid or plastic condition and which harden upon being deprived of moisture.

In building operations it is well known that much construction work employs temporary forms into which or upon which concrete mix is poured to form, when hardened, a wall or floor. In many instances it is desired to hang pipes, fixtures or the like upon these walls or suspend them from a ceiling. Therefore, it is desirable that a hole be pre-formed in the concrete for fastening the object thereto. Where it is desired to mount a fixture or a bracket, it is desirable to have a threaded nut imbedded in the concrete at the bottom of the hole whereby the fixture or bracket may be threadedly connected. It is especially advantageous that the means for forming such hole or for positioning the nut be readily removable, both with respect to the hardened concrete and also the temporary forms.

Among the objects of the invention are to provide a device for pre-forming a hole or for positioning a threaded nut or the like in a plastic body which hardens upon setting. Another object is to provide for positioning a nut or the like in a predetermined position relative to forms into which plastic material is to be poured, and which device may be readily removed from the plastic material after it has hardened, leaving the nut imbedded at its predetermined position. A further object is to provide a removable concrete insert block which is economical in manufacture, efficient in operation and labor saving in the pre-forming of holes in concrete and for the setting of nuts and the like therein.

With the foregoing and other objects in view, all of which will be more apparent as this specification proceeds, the invention is exemplified in one form in the novel construction and combination of parts hereinafter described, illustrated in the accompanying drawing, and pointed out in the claims hereto appended, it being understood that various changes in the form, proportion, size and details of construction of the apparatus may be resorted to within the scope of the appended claims without departing from the spirit or sacrificing any of the advantages of the invention.

To more clearly comprehend the invention, reference is directed to the accompanying drawing, wherein:

Fig. 1 is a side elevation of the invention partly in section.

Fig. 2 is a front view of a key locking plate.

Fig. 3 is a side elevation partly in section of a modified form of the device shown in Fig. 1.

Fig. 4 is a side elevation partly in section of another modified form of device shown in Fig. 1.

Fig. 5 is a fragmentary perspective view of the structure shown in Fig. 4.

Fig. 6 is a side elevation partly in section of a modified form of the invention.

Fig. 7 is a bottom view of the structure of Fig. 6.

Referring to the drawing in which like reference characters indicate corresponding parts in the several views, 10 is a shank of a pole-like plug member, preferably tapered conically from a central portion toward one end. Where the device is desired for use in setting a nut into concrete, the end of smaller diameter of the tapered shank is provided with threads 11 for mounting thereon of a correspondingly threaded nut 12; and therebeyond the said end may have a portion of lesser diameter which provides an integral rounded head or button 13 which will pass through the opening in the nut and provide a button which may be hammered without mutilation of the threads at the tapered end of the shank. The end of the tapered shank of smaller diameter is of slightly larger diameter than its adjacent threaded portion so that the threads may readily pass through the opening left in the concrete upon removal of the insert plug from the hardened concrete body.

The opposite end of the shank is for insertion in one wall of the body of the usual temporary pouring forms, which, in the case of a vertical wall, are relatively spaced and between which the semi-fluid concrete is poured; whereas, in the case of a horizontal floor or ceiling there may be only one horizontal form, usually called a deck 14, which is illustrated herein as exemplifying one use to which the invention may be put.

In Fig. 1 said opposite end of the shank is provided with a fixed axially extended stub member 15 which preferably has its side walls flattened for engagement by a wrench, such walls being illustrated herein as hexagonal in lateral transverse section. After the temporary forms have been erected, suitable holes 16 are bored at predetermined places in the forms and the stub 15 is inserted therein, preferably having engagement with the walls of the hole along the angles formed

by the intersecting planes of the stub walls and thereby providing sufficient grip between the stub and the forms so that the stub will normally be held in place in a circular hole and yet not provide such a large frictionally engaged area so that it will be difficult to remove the forms after the concrete has hardened. If the fit of the stub 15 in hole 16 is substantially snug, a hammer may be employed to tap the head or button 13 and drive the plug into the hole. To further insure the maintenance of the device in the form against inadvertent removal such as striking thereagainst of the foot of a workman on a deck or by the pouring and agitation of the concrete mix, a releasable locking means indicated 17 is provided. In Fig. 1 this locking means comprises a machine screw 18 threadedly engaging a threaded recess in the stub 15, and a slotted key plate 19 having an opening 20 through which the head of screw 18 may be inserted and a narrower communicating slot 21 in which the shank of the screw may slide. Other forms of releasable locking means may also be employed, but the screw and key plate in Fig. 1 provide the advantage of being adjustable in the event that the forms are of greater thickness than the length of the stub 15. Intermediate the ends of the insert plug and preferably at the juncture of the tapered shank 10 and the stub 15 there is provided a fixed radially extending shoulder flange 22 providing at one face a base 23 and having its opposite face tapered upwardly and inwardly, preferably arcuately as at 24 from the circumferential edge of the shoulder flange toward the base of the tapered shank.

In the modifications of Figs. 3, 4 and 6 of the members 10, 11, 12, 13 and 22 may be the same as in Fig. 1.

It may sometimes happen in pouring forms for vertical walls where two spaced forms are necessary that the setting of a concrete insert plug may have been inadvertently omitted until the forms have reached an elevation far above the points at which it is desired to place one of the insert plugs. Usually the form of device shown in Fig. 1 may be utilized in such an instance by cutting the usual hole 16 in the form and piloting the removable insert plug down between the forms on a suspended wire and feeding the stub 15 into the hole by fishing with any sort of suitable hook or bent wire inserted through the hole. However, if this is impractical, either because of location of the omitted removable insert plug or because of having omitted a large number of them, the modifications of Figs. 3 and 4 are advantageous.

In the modification of Fig. 3 the hole 16a is cut into the form at the desired place and the assembly of shank 10, nut 12 and shoulder flange 22, together with a filler member or collar 25, are inserted through the hole. Manifestly the hole 16a must be cut of sufficient diameter to receive such member therethrough. The filler member or collar 25 fills the vacancy around the stub 15 so as to provide a snug fit in the hole 16a. The key plate 19 may be employed as a releasable locking means and the device stabilized relative to the form by nails 26 driven through the ends of slot 21 and into the forms. Similar nails for a similar purpose may also be employed if desired in the device indicated in Fig. 1.

In Figs. 4 and 5 a modification is shown wherein the stub member 15a is provided with two flat sides 27 and has intervening portions of its circumference threaded as at 28. Thus, the flat sides are suitable for engaging a tool for removal of the

device, as hereafter explained, and the threads serve to engage a recessed nut 29 in which the collar portion 30 fills the vacant area of an enlarged hole 16a, and the top or cap 31 serves as a flange-engaging the outer face of the pouring forms to stabilize the insert plug in position. Nails 26 may also be employed to further stabilize the insert device, especially if the device were being used in overhead forms.

- 10 In the modification of Fig. 6 the stub for engaging in the pouring forms comprises a spike member 15b which may be driven into the body of the pouring forms. Where the spike member 15b is employed, it is preferred that it be four-sided and tapered similar to a pyramid having its sides arcuate or dished at their base, as indicated in 15c in Fig. 7 so that the frictional grip in the body of the forms will be over a diminished area. In operation the insert plugs are set in the body of the forms at predetermined places, those of the types of Figs. 1, 3 and 4 being suitable holes cut in the forms to receive them, and the modification of Fig. 6 being driven into the body of the form. The locking means 17 is then engaged and nailed, if necessary. Where it is desired to imbed a nut in the concrete, the nut 12 is mounted on the threaded end of the shank when the insert plug is positioned in the forms. The concrete or the like is then poured into the prepared temporary forms, agitated where necessary to settle it and permitted to harden in the usual manner. Obviously, the concrete surrounds the shank 10 of the insert plug and including the nut 12; and the tapered face 24 of the flanged shoulder member 22 is imbedded in the face of the concrete with the opposite face or base of the flanged shoulder substantially co-planar with the face of the concrete, while the stub member is engaged in the body of the forms. After the concrete hardens to the desired extent, the locking means is removed from the stub and the temporary pouring forms are likewise removed. This leaves the insert plug set in the hardened concrete with the stubs 15, 15a, 15b extending from the face of the concrete. The stub being of such shape as to be readily engaged by a tool such as a wrench, may be gripped for axial rotation. Manifestly, the nut 12, which will be of the angular type, will not rotate with the shank, but will remain set in the hardened concrete. Because of the upward and inward incline of the upper wall 24 of the shoulder flange and the taper of the shank 10, those members will break the seal with the concrete very readily, whereupon the plug may be pulled from the formed hole in the concrete wall. Where the nut 12 is employed, it becomes fixedly imbedded at its predetermined position in the concrete and the rotation of the shank relative thereto releases the shank for removal from the nut. In fact, the relative threaded engagement of the shank and nut facilitates the removal of the shank from the concrete upon rotation of the shank, since the pitch of the co-operating threads forces the shank and shoulder flange from their seats in the concrete.

It is to be understood that I have used the term concrete herein in a generic sense to include all types of plastic or moldable material which may be poured or formed in a fluid or semi-fluid state and hardened thereafter. The mode of operation of the device would be identical in use with all such materials.

Having thus described the invention, what is claimed as new and patentable is:

1. A removable concrete insert device compris-

ing a plug having a tapered shank at one end portion and having at its opposite end an integral stub extension portion adapted for engagement into the body of pouring forms, and said plug having intermediate its stub and shank an integral radially, outwardly extended shoulder member which has one of its faces smooth and tapered inwardly and upwardly toward the tapered end of the shank.

2. A removable concrete insert device comprising a plug having a shank at one end portion, the said shank being threaded for mounting a nut adjacent its terminal end, said plug having at its opposite end an integral stub extension portion adapted for engagement into the body of pouring forms, and said plug having intermediate its stub and shank an integral radially, outwardly extended shoulder member having one face smooth and tapered inwardly and upwardly toward the nut-receiving end of the shank.

3. A device of the character described, including a tapered shank at one end portion and having its smaller end threaded for mounting a nut, said plug having at its opposite end an integral stub extension portion adapted for engagement into the body of pouring forms and said plug having intermediate its stub and shank a radially, outwardly extended shoulder member which has one of its faces smooth and tapered inwardly and upwardly toward the tapered end of the shank.

4. A removable concrete insert device comprising a plug having a tapered shank provided at its smaller end portion with a thread to receive a threaded nut and having a portion extending therebeyond of lesser diameter than the threaded portion, said plug having at its opposite end an integral stub extension portion adapted for engagement in the body of pouring forms and having its sides flattened for engagement by a tool, and said plug having intermediate its stub and shank an integral radially, outwardly extended shoulder member having one face tapered toward the smaller end of the shank.

5. A device of the character described, including a tapered shank having at its smaller end a portion adapted for mounting a nut, said plug having at its opposite end an integral stub extension portion adapted for engagement into the body of pouring forms and having locking means for releasable engagement by a lock member, said plug having intermediate its stub and shank an integral radially, outwardly extended shoulder member having a smooth face tapered toward

the smaller end of the shank, and a lock member for releasably engaging the locking means of the stub, whereby the plug may be secured against inadvertent removal relative to the pouring forms.

6. A removable concrete insert device comprising a plug having a tapered shank provided at its smaller end with a portion adapted for mounting a nut, said plug having at its opposite end a stub extension portion adapted for engaging into the body of pouring forms, said plug having intermediate the tapered shank and stub an integral radially, outwardly extended shoulder member providing a flat base at one face thereof for contacting the forms and having its opposite face smoothly tapered inwardly and upwardly toward the nut-receiving end of the shank.

7. A concrete insert device of the character described, including a tapered shank having at its smaller end portion a thread to receive a threaded nut and having a portion extended therebeyond of lesser diameter than the threaded portion, said plug having at its opposite end an integral stub extension portion adapted for engagement into the body of pouring forms and provided with flattened sides for engagement in removing the plug from poured concrete, a shoulder member intermediate the stub and shank and extending radially outwardly from the axis thereof, said shoulder member having one of its faces tapered inwardly and upwardly toward the nut-receiving end of the shank.

8. A removable concrete insert device comprising a plug having a shank tapered from a base toward an end portion threaded to receive a threaded nut and having a portion extended therebeyond of lesser diameter than the threaded portion, said plug having at its opposite end a stub extension portion adapted for engagement into the body of pouring forms, said stub having flattened sides for engagement in removing the plug from poured concrete and having locking means for releasable engagement by a lock member, an integral shoulder member intermediate the stub and shank and extending radially outwardly therefrom, one of the faces of said shoulder member being tapered smoothly inwardly and upwardly toward the nut-receiving end of the shank, and a lock member for releasably engaging the locking means of the stub, whereby the stub may be secured against inadvertent removal relative to the pouring forms.

IR A G. HASKELL.
